UNITED STATES PATENT OFFICE.

EDWARD B. NOWOSIELSKI, OF BLOOMFIELD, NEW JERSEY, ASSIGNOR TO SPLITDORF ELECTRICAL COMPANY, OF NEWARK, NEW JERSEY.

RECEIVER.

Application filed April 12, 1922. Serial No. 551,873.

To all whom it may concern:

Be it known that I, EDWARD B. Nowosiel-
ski, a citizen of the United States, residing
at Bloomfield, in the county of Essex, State
5 of New Jersey, have invented certain new
and useful Improvements in Receivers, of
which the following is a description, refer-
ence being had to the accompanying draw-
ing, and to the figures of reference marked
10 thereon.

This invention is directed to an electric
current receiver suitable for receiving cur-
rents set up by the voice or radio waves and
such like.

15 It is the principal object of my invention
to provide a receiver which is first of all
highly efficient, yet one in which the con-
struction is very simple whereby the cost of
manufacture may be reduced to a minimum.
20 Particular attention is directed to the de-
tails of construction which will be herein-
after set forth, as it will be seen that I have
eliminated all drilling and tapping of holes
in the receiver casing, the only threads at
25 all being on the body part of the casing
where the ear piece is screwed on.

The construction of my receiver is such
that the assembly operations are reduced to
a minimum as will be apparent from the de-
30 scription and drawing, wherein:

Figure 1 is a plan view of the receiver
with the ear cap and diaphragm removed.

Figure 2 is a section on the line 2—2 of
Fig. 1.

35 In the drawings, 1 is the body of the cas-
ing having an ear cap 2 with a diaphragm 3
held in proper operative position. While
the diaphragm 3 is shown as held on the rim
of the casing 1 by the cap 2, it will be un-
40 derstood that the diaphragm may be held in
any other suitable manner; also the casing 1
may be of any suitable material, but for cer-
tain purposes I prefer to use a metal body of
any non-magnetic material such as alumini-
45 num. The casing 1 has a stud 4 which is
used for mounting the receiver on a head
band. This feature will be referred to in a
separate application covering a particular
type of head band. The side wall of the
50 casing 1 has an aperture therein and posi-
tioned in this aperture is a terminal block 5
which is shouldered at 6, whereby the re-
duced portion of the terminal block 5 may
be inserted through the aperture from the
55 inside of the casing, shoulder 6 acting as a

seat for the block. The terminal block 5 is
preferably of insulating material and has
terminals 7 and 8 moulded therein for the
purpose of receiving cable ends 9 and 10
which are fastened therein by screws 11. It 60
will be understood the block 5 may be made
of non-magnetic metal with proper insula-
tors set therein. The inner edges 12 of the
terminal block are preferably tapered to-
ward the center of the casing to receive the 65
ends of the magnet 13, which engage the
said surfaces 12 for a reason which will be
presently pointed out. The magnet 13 is
preferably of one-piece construction, rectan-
gular in cross-section and set edgewise in 70
the casing. It will be noted that the mag-
net is circular in form and forms nearly a
complete circle. The ends of the magnet
are formed or milled off to form a flat posi-
tioning surface for the pole pieces 14 and 75
15. These pole pieces are preferably of
laminated construction as shown and are
substantially T-shaped, the vertical portion
of the T resting against the inner faces of
the ends of the magnet, while the horizontal 80
portions 16 have one end resting against the
bottom of the casing 1 and the upper ends
17 extending to the proper working distance
from the diaphragm 3. The vertical por-
tions of the pole pieces having windings 18 85
and 19 thereon, the outer ends of the wind-
ings being connected to the terminals 7 and
8. As will be seen from the drawing the
pole pieces 14 and 15 extend toward the cen-
tral portion of the casing and the horizontal 90
portions 16 are engaged by a bridge mem-
ber 20 that is milled out so as to securely
clamp these ends of the pole pieces, holding
them in properly spaced relationship. The
bridge 20 is screw threaded for the reception 95
of a stud 21 that abuts against the magnet 13
at 22 substantially diametrically opposite
the terminal block.

In the assembly of my receiver, the termi-
nal block 5 is put into position as already de-
scribed, the magnet 13 dropped into place,
windings 18 and 19 slipped onto the pole
pieces 14 and 15, which are then placed in
position so that their ends also abut against
the surface 12 of the block 5, as well as 100
against the ends of the magnet 13. The
bridge 20 to which the stud 21 has already
been assembled is then placed over the por-
tion 16 of the pole pieces and a wrench ap-
plied to the hex portion 23, forcing the 110

bridge 20 radially against the pole pieces which in turn press against the magnet 13 and thereby press against the block 5 on the tapered surfaces 12, when the stud 21 has 5 been set up so that the parts are all securely in position. The lock nut 24 is screwed down against the bridge 20 and the final operation of finishing the air gap between the diaphragm and ends 17 can be performed.

10 From the above description it will be particularly noted that there are no tapped holes in the receiver casing and that the entire assembly of the parts can be performed in a matter of seconds. To the terminals 7 15 and 8 are attached gap terminals 25 and 26 which are sometimes used for the purpose of taking care of static disturbances.

The pole pieces herein described are of such construction that the length of turns on 20 the windings 18 and 19 are relatively short so that I can use a larger wire than ordinarily used, particularly for radio receivers; at the same time securing a large number of turns whereby I get the maximum effect be- 25 tween the windings and the magnetic field set up by the magnet. I have found that this construction enables me to use a thicker diaphragm than ordinarily used for radio work and this thicker diaphragm is more 30 susceptible to high frequencies as its natural period of vibration is higher than that of a thinner diaphragm.

It will be understood by one skilled in 35 this art that my invention is susceptible of a number of changes in the actual details of construction, but it is my intention to cover these equivalent forms in the appended claims.

Having thus described my invention, 40 what I claim is:

1. In a device of the class described, a casing 45 consisting of, a body and an ear piece with a diaphragm associated therewith, a magnet having pole pieces abutting against its extremities, said pole pieces extending toward the central portion of the casing into operative relationship with the diaphragm and having windings thereon and means pressing against said pole pieces at 50 points near the central portion of the casing for holding them securely against the magnet ends.

2. In a device of the class described, a casing 55 consisting of, a body and an ear piece with a diaphragm associated therewith, a one piece magnet having pole pieces abutting against its extremities, said pole pieces extending toward the central portion of the casing into operative relationship with the diaphragm and having windings thereon and means abutting against the magnet at a point some distance from the point of contact of said pole pieces with the magnet and pressing against the pole pieces 60 at points near the central portion of the

casing for holding the magnet and pole pieces in position in the casing.

3. In a device of the class described, a casing consisting of, a body and an ear piece with a diaphragm associated therewith, 70 a one piece magnet having pole pieces abutting against its extremities, said pole pieces extending toward the central portion of the casing into operative relationship with the diaphragm and having windings 75 thereon, a bridge engaging the inner ends of said pole pieces, a stud screw threaded into said bridge and abutting against said magnet for holding the pole pieces and magnet in position in the casing.

4. In a device of the class described, a casing consisting of, a body and an ear piece with a diaphragm associated therewith, a one piece magnet having pole pieces abutting against its extremities, said pole pieces 85 extending toward the central portion of the casing into operative relationship with the diaphragm and having windings thereon, a bridge of non-magnetic material having notches to grip the inner ends of said pole 90 pieces, and a non-magnetic stud screw threaded into said bridge and abutting against said magnet for holding the pole pieces and magnet in position in the casing.

5. In a device of the class described, a casing 95 consisting of, a body and an ear piece with a diaphragm associated therewith, a one piece magnet rectangular in cross-section set edgewise within the casing, pole pieces abutting against the inner faces of 100 its ends and extending toward the central portion of the casing into operative relationship with the diaphragm and having windings thereon, a bridge of non-magnetic material having notches to hold the inner 105 ends of the pole pieces in spaced relationship and a non-magnetic stud abutting against the magnet and engaging said bridge to cause it to press the said pole pieces into engagement with the magnet 110 ends.

6. In a device of the class described, a casing 115 consisting of, a body and an ear piece with a diaphragm associated therewith, a magnet having pole pieces abutting against its extremities, said pole pieces being made up of T-shaped laminations, the vertical portion of the T having windings thereon and abutting against the ends of the magnet, while the horizontal portion of the T 120 has one end resting against the bottom of the casing and the top extending into position to act on the diaphragm, a bridge engaging the horizontal portion of the T, a stud abutting against the magnet and forcing the bridge, pole pieces and magnet into 125 a locked position in the casing.

7. In a device of the class described, a casing 130 consisting of, a body and an ear piece with a diaphragm associated therewith, a

one piece magnet forming nearly a complete circle, pole pieces engaging the inner part of the ends of said magnet and extending toward the central part of the casing, a bridge member engaging the inner ends of said pole pieces holding them in spaced relationship, windings on said pole pieces, a stud positioned in the central part of the magnet and engaging said bridge and having means for forcing the bridge against the pole pieces to bind them and the magnet in position in the casing.

8. In a device of the class described, a casing consisting of, a body and an ear piece with a diaphragm associated therewith, a magnet, pole pieces for the magnet, windings on said pole pieces, a bridge for engaging said pole pieces and a stud abutting against the magnet and engaging the bridge to force the bridge, pole pieces and magnet into working position in the casing.

9. In a device of the class described, a casing consisting of, a body and an ear piece with a diaphragm associated therewith, a one piece magnet forming nearly a complete circle, pole pieces engaging the inner part of the ends of said magnet and extending toward the central part of the casing, a bridge member engaging the inner ends of said pole pieces holding them in spaced relationship, windings on said pole pieces, a stud positioned in the central part of the magnet and engaging said bridge and having means for forcing the bridge against the pole pieces to bind them and the magnet in position in the casing, an aperture in the side wall of the casing and a terminal block positioned in the aperture and in the opening between the ends of the magnet.

10. In a device of the class described, a casing consisting of, a body and an ear piece with a diaphragm associated therewith, an aperture in the side wall of the casing, a terminal block positioned in said aperture, a magnet having its ends abutting against said block, pole pieces for the magnet with windings thereon, a bridge member engaging the pole pieces and a stud abutting against the magnet and adapted to hold the bridge, pole pieces, magnet and block in operative position in the casing.

11. In a device of the class described, a

casing consisting of, a body and an ear piece with a diaphragm associated therewith, an aperture in the side wall of the casing, a terminal block positioned in said aperture, said block having its inner sides somewhat tapering toward the center of the casing, a magnet having its ends abutting against the tapered sides of the block, pole pieces engaging the ends of said magnets so as to bear jointly with the magnet ends against the tapered sides of the block, windings on said pole pieces, a bridge engaging and supporting the inner ends of the pole pieces and means for forcing the pole pieces and magnet against the block and the casing.

12. In a device of the class described, a casing consisting of, a body and an ear piece with a diaphragm associated therewith, a magnet having pole pieces to act on the diaphragm, windings on said pole pieces, a terminal block of insulating material having terminals connected to said windings, a spark gap carried by said terminals within the casing, a bridge engaging said pole pieces and a single means for locking said block, magnet, pole pieces and bridge in operative position within the casing.

13. In a device of the class described, a casing consisting of, a body and an ear piece with a diaphragm associated therewith, a one piece magnet rectangular in cross-section placed edgewise in the casing, a terminal block of non-magnetic material positioned between the ends of the magnet and having terminals insulated from each other, T-shaped pole pieces having the vertical part of the T resting against the ends of the magnet alongside the block, windings on the pole pieces and connected to said terminals, the horizontal portion of the T resting against the bottom of the casing and extending to a point near the diaphragm, a bridge engaging this latter part of the pole pieces and a device for forcing the bridge against said pole pieces to lock them, the magnet and block in position in the casing.

In testimony whereof, I affix my signature.

EDWARD B. NOWOSIELSKI.
